UNITED STATES PATENT OFFICE

140,720

DESIGN FOR A TOY BOAT

Walter L. Ripley, Sharpsburg, Md., assignor of one-half to Gladys A. Ripley, Sharpsburg, Md.

Application June 30, 1944, Serial No 114,270

Term of patent 14 years

(Cl. D34—15)

To all whom it may concern:

Be it known that I, Walter L. Ripley, a citizen of the United States, residing at Sharpsburg, in the county of Washington and State of Maryland, have invented a new, original, and ornamental Design for Toy Boat, of which the following is a specification, reference being had to the accompanying drawing forming a part thereof.

Figure 4 is a front elevational view; and
Figure 5 is a rear elevational view thereof.
I claim:
The ornamental design for a toy boat, as shown.

WALTER L. RIPLEY.
